UNITED STATES PATENT OFFICE.

JOHN WINN, OF BROOKLINE, AND AARON FEINBERG, OF DORCHESTER, MASSACHUSETTS.

SAFETY-LOCK.

1,193,653.

Specification of Letters Patent. Patented Aug. 8, 1916.

Application filed September 3, 1914. Serial No. 859,942.

To all whom it may concern:

Be it known that we, JOHN WINN, a citizen of the United States, and a resident of Brookline, county of Norfolk, Commonwealth of Massachusetts, and AARON FEINBERG, a citizen of the United States, and a resident of Dorchester, county of Suffolk, Commonwealth of Massachusetts, have invented certain new and useful Improvements in Safety-Locks, of which the following is a specification accompanied by drawings.

This invention relates to safety locks, but more particularly to a safety guard or shutter adapted to be applied to the lock strike and designed to prevent the insertion of a flexible piece or tool between the door and door jamb for the purpose of forcing the bolt backwardly.

20 In a spring latch lock, of ordinary construction, there is usually more or less space or clearance between the door and door jamb, and a flexible tool may be inserted without much difficulty into this space from the outside, and manipulated to force back the bolt to open the door. The tool may be inserted between the edge of the door and the jamb or else a hole may be cut through the corner of the door to make a more direct 30 entrance for the tool.

Our guard or shutter is so constructed that it will effectually prevent the forcing of the lock by any of these methods, and our device is operated automatically by the 35 closing and opening of the door.

Further objects of the invention will hereinafter appear and the invention is shown in the accompanying drawings, in which—

Figure 1 is a horizontal sectional view of 40 devices embodying the invention; Fig. 2 is a similar view partly broken away of the guard or shutter in normal position. Fig. 3 is a front view of Fig. 2; and Figs. 4 and 5 are horizontal sectional views, partly 45 broken away of modifications.

Referring to the drawings, A represents a portion of a door, having the lock casing B therein, C is the door jamb, and D is the strike. The bolt E has the usual beveled 50 head F and slides in the lock casing.

In Figs. 1, 2 and 3 we have shown one form of guard movably mounted at the opening of the strike D. The beveled end F of the bolt forces one portion of the guard inwardly, as 55 the door is closed, and the other portion of

the guard is swung outwardly as shown in Fig. 1, into the space between the door and door jamb.

The guard may be constructed in various ways, and one form of construction shown in 60 Figs. 1, 2 and 3 comprises two members G and H, pivoted on a common pivot J in any suitable manner, as by means of the lugs K and L on the respective members.

In order to cause the guard to return to 65 normal position when the bolt is withdrawn, I provide a retracting spring O of any suitable construction, shown as a coiled spring coiled about the pivot J and having one end a bearing on the member G and the other 70 and longer end b abutting against the edge of the opening in the strike.

Another spring P is coiled about the pivot J and has one end c bearing on the member G and the other end d bearing against the member H, so that as the member G is 75 pressed inwardly by the bolt, the member H is forced outwardly through the intermediary of the spring P, and this spring connection permits relative movement between 80 the members G and H. The member G may be rocked about its pivot to a greater angular extent than the member H, as indicated in Fig. 1, and the member H will always be tightly pressed against the door. If desired, 85 a recess Q may be formed in the door or in a portion of the lock casing as shown, for the reception of the end of the member H, and thus further and absolutely prevent the insertion of a tool by force to press back the 90 bolt.

We are not to be understood as limiting the invention to two rigid members G and H, connected by a spring, and we have shown two other equivalent constructions 95 which will illustrate modifications.

In Fig. 4 one portion of the guard or shutter is formed of a rigid or stiff member R having suitably secured thereto a spring member S. The member R is provided with 100 lugs T pivoted on the pivot J as before. In this case the flexibility of the device is afforded by the spring member S, and an additional retracting spring O only is provided, having one end a bearing against the 105 spring member S and the other end b having an abutment against the edge of the strike as shown.

In Fig. 5 a flexible guard or shutter is provided in one piece, comprising a spring 110

U secured to the lugs V and pivoted on the pivot J. The retracting spring O is also provided for this spring guard.

The constructions specified may be further modified as desired without departing from the spirit of the invention. It is especially necessary, not only to prevent the insertion of a flexible piece or tool between the door and door jamb, but to guard against a favorite trick of the thief, which consists in boring through the corner of the door or lock casing along the dotted line W indicated in Fig. 1, so that a more direct passage may be afforded for the insertion of the burglar's tool. Our guard will effectively block the insertion of a tool in this way, as well as directly through the space between the door and the door jamb.

Our device is so constructed that it may be applied to almost any existing lock of the type specified herein, and the provision of flexibility in the device enables it to be used with bolts of different sizes, or which travel longitudinally different distances.

We claim and desire to obtain by Letters Patent the following:

1. In a spring-latch lock, the combination with the lock casing, bolt having a beveled end, and strike, of a guard pivoted at the opening of the strike, one portion of the said guard being adapted to be pushed inwardly by the bolt, so that the remaining portion of the guard is swung outwardly to form an obstruction in the space between the door and door jamb and a retracting spring for returning the guard to normal position when the bolt is withdrawn, the said portion of the guard which is adapted to be pushed inwardly by the bolt being capable of greater angular movement about

the pivot than the remaining portion of the guard.

2. In a spring-latch lock, the combination with the lock casing, bolt having a beveled end, and strike, a two piece guard, a common pivot located at the opening of the strike, the members of said guard being pivoted on said pivot, independent springs for each of the members of said guard, so that one member of the guard may rock about the pivot to a greater extent than the other, the bolt being adapted to push one member of the guard inwardly and thereby carry the other member outwardly into the space between the door and door jamb.

3. In a spring-latch lock, the combination with the lock casing, bolt having a beveled end, and strike, a two piece guard, a common pivot located at the opening of the strike, the members of said guard being pivoted on said pivot, independent springs for each of the members of said guard, so that one member of the guard may rock about the pivot to a greater angular extent than the other, the bolt being adapted to push one member of the guard inwardly and thereby carry the other member outwardly into the space between the door and door jamb, the lock casing having a recess to receive the end of the other member of the guard which is swung outwardly into the said space between the door and door jamb.

In testimony whereof we have signed this specification in the presence of two subscribing witnesses.

JOHN WINN.
AARON FEINBERG.
